UNITED STATES PATENT OFFICE.

RUBY LEFI, OF NEW YORK, N. Y.

DESIGN FOR A STOCKING.

Application filed May 14, 1928. Serial No. 26,663. Term of patent 14 years.

To all whom it may concern:

Be it known that I, RUBY LEFI, a citizen of the United States, and a resident of the city of New York, in the county of New York and State of New York, have invented the new, original, and ornamental Design for a Stocking, of which the following is a specification.

Reference is had to the accompanying drawing, forming part thereof, wherein

I claim:

The ornamental design for a stocking, substantially as shown and described.

Signed at New York, in the county of New York and State of New York, this 10th day of May, A. D. 1928.

RUBY LEFI.
